SPLITTING MACHINE

Charles E. Hood, Lynn, Mass., assignor to United
Shoe Machinery Corporation, Paterson, N. J.,
a corporation of New Jersey

Application October 3, 1938, Serial No. 232,965

25 Claims. (Cl. 69—13)

This invention relates to splitting machines and is herein illustrated as embodied in a machine particularly adapted to remove a thin split or skiving from the grain side of a piece of leather such as an insole.

Machines of this type commonly comprise a knife, an internally yieldable roll, for example a rubber roll, and a work support or table having an unyielding gaging edge or corner against which the work is progressively pressed by the roll as the work is fed to the knife. The skiving which is removed is usually very thin; and to ensure the removal of such a thin continuous skiving of uniform thickness it is desirable that the gaging edge or corner be parallel to and below the axis of the roll, parallel to and a certain distance in front of the edge of the knife and at a certain level below said edge, the distance of said edge below the level of the edge of the knife determining the thickness of the skiving which will be removed from the work.

According to one feature of the invention the member which carries this unyielding gaging edge is mounted for adjustment bodily in two directions and for angular adjustment about two axes which are at an angle to each other. In the illustrated embodiment this member is the work support or table; and any one of the four adjustments may be made independently of the three others by manipulating a selected one of four knobs or hand holds.

The knife is adjustable bodily and angularly as is usual in such machines; and to facilitate the proper adjustments of the knife and the member which carries the unyielding gaging edge, there are provided, in accordance with another feature of the invention, indicating mechanisms which indicate when the proper adjustments have been made. In the illustrated machine there are two pairs of pointer-and-scale mechanisms, one pair for the knife and the other for the work support or table which carries the gaging edge.

Machines of this general type are used very commonly in the shoe industry to remove thin grain skivings from insoles; and it is desirable, in those cases in which the practice at the factory permits it, to provide means for feeding insoles or other pieces of work rapidly to the roll and a knife. To this end there is provided, in accordance with another feature of the invention, means for supporting a stack of pieces upon a run of a belt and means for operating the belt to feed the pieces one at a time from the bottom of the stack to the knife and roll; and preferably

a receiving receptacle is provided in which the finished pieces are received and stacked.

These and other features of the invention, including certain details of construction and combinations of parts, will be described as embodied in an illustrated machine and pointed out in the appended claims.

Referring to the accompanying drawings:

Fig. 1 is a front elevation of a machine in which the present invention is embodied; 10

Fig. 2 is a plan of the machine;

Fig. 3 is a longitudinal section on the line III—III of Fig. 2;

Fig. 4 is a view, partly in section and partly in elevation, of the right-hand end of the machine 15 as viewed in Figs. 1 and 3, the magazine and the parts associated with it having been removed;

Fig. 5 is a view, partly in plan and partly in section, of a portion of the machine, the feed magazine and the feed roll having been omitted, 20 and part of the table having been broken away; and

Fig. 6 is a section on the line VI—VI of Fig. 5.

Referring first to Fig. 3, the general operation of the machine will be described before taking up the details of its construction. The pieces of work, herein shown as insoles, are fed grain side down one by one from a magazine over a flat table 9, the forward operative end of which consists of a hardened block 11, to a stationary knife 13 and a rubber covered roll 17 which cooperate with the unyielding gaging edge formed by the forward corner or edge of the hardened block to remove from the lower face of the work a thin skiving 200. The skivings pass down a chute 19; and the insoles, from which the thin grain skivings have been removed, are carried into a receptacle and stacked. The rubber roll, the knife and the hardened block, which forms the operative forward end of the table 9, act as do the corresponding elements of the machine disclosed in United States Letters Patent No. 1,260,436, granted March 26, 1918, upon an application filed in the name of Thomas J. O'Keeffe, the height of the edge of the knife above the adjacent edge or corner of the hardened block determining the thickness of the skiving which is removed and the rubber roll yielding to inequalities in the thickness of the work.

It is desirable that the skivings removed from the work should be as thin as possible, for example of the order of from .002 to .003 of an inch, so as not to waste any considerable amount of stock, and that they should be continuous so as to leave clean, unbroken surfaces on the skived work. 55

Means is therefore provided for adjusting the parts of the machine so that the operative edge or corner of the hardened block shall be directly below and parallel to the axis of the rubber roll 5 and so that the edge of the knife 13 and the adjacent operative corner of the hardened block 11 shall be in exact parallel relation and distant from each other both horizontally and vertically by the proper amounts. The table or work support 9 (Fig. 1) has four legs, one approximately at each corner, having flat lower ends which rest upon flat surfaces formed on a support 27 so that the table may be adjusted forward and back as well as angularly. In order to effect such adjustment the table is mounted for horizontal sliding movement toward and from the knife upon a block 21 which is pivoted about a vertical axis. Referring to Fig. 4, the table 9 has an undercut guideway in which the opposite upwardly flaring edges of the block 21 are received. The block is held stationary, except while the table is being adjusted (at which time, as will presently appear, it may be swung angularly) by a screw 23 the flat head of which is received in a recess in the upper 10 side of the block and is fastened to the block by a small screw 25. The stem of the screw 23 passes down through a bore in the support 27 (Fig. 3) and has threaded on its lower end a nut 29 through which passes a small bar 31 by which 15 the nut may be turned. When the nut is tight the table 9 is held rigid with and locked to the block 21 and the support 27. When the nut is loose the table may slide on the block, and both the table and the block may be swung together about the 20 axis of the pivot screw 23. Referring to Fig. 5, the table 9 is urged at all times to move toward the knife 13 by two compression springs 33, 35, one end of each spring being located in a socket in the block 21 and the other end engaging a 25 downwardly extending lug (Fig. 3) on the forward end of the table. Referring again to Fig. 5, the tendency of the springs to move the table 9 toward the knife is opposed by two cams in the form of wedges 37, 39 which engage with their forward 30 inclined faces stops in the form of vertical rolls 41, 43 carried by the support 27. The opposite flat alined faces of the wedges are in sliding engagement with flat faces formed on a casting 45, said casting being fastened to the table 9 by 35 screws 47 and serving as a support for the feeding magazine which will be described later. The wedge 39 is fastened by a pin 49 to a rod 51 which passes through the wedges, said rod having on its right-hand end, as viewed in Fig. 5, a left- 40 hand thread and on its left-hand end a right-hand thread. A coiled compression spring 53, which bears with its right-hand end against a 45 part of the table 9 and with its left-hand end against the bottom of a recess in the wedge 39, urges the wedge and the rod at all times to move 50 toward the left, the location of the wedge and the rod at any time depending upon the position of a knob 55 which is threaded on the right-hand end of the rod and abuts with its left-hand end a boss 55 on the table 9. A second coiled compression spring 57, which bears with its right-hand end against the left-hand end of the wedge 39 and with its left-hand end against the bottom of a 60 socket in the wedge 37, urges the wedge 37 at all 65 times to move along the rod 51 toward the left as far as is permitted by a second knob 59 which is threaded on the left-hand end of the rod 51 and abuts the left-hand end of the wedge 37. With 70 this construction, when the nut 29 has been 75 loosened, the table 9 may be adjusted bodily for

ward and back toward and from the edge of the knife as well as angularly in a horizontal path about a vertical axis of the screw 23. To adjust the table bodily toward the knife the knob 55 is turned right hand on the left-hand thread of the rod as indicated by the arrow. This permits the spring 53 to move the rod and the wedges 37, 39 to the left whereupon the springs 33, 35 move the table 9 bodily toward the knife 13. Turning the knob 55 in the opposite direction moves the wedges 37, 39 to the right and moves the table away from the knife. To swing the table 9 about the axis of the screw 23 so as to aline the operative edge of the table 9 (that is the operative corner of the hardened block 11) with the axis of the feed roll, the knob 59 is turned to cause the wedge 37 to be moved along the rod 51 independently of the wedge 39. Turning the knob 59 left-hand on the right-hand thread of the rod, as indicated by the arrow, causes the wedge 37 to be moved to the left by the spring 57 and thereby permits the left-hand end of the operative corner of the hardened block 11 to be swung toward the knife by the spring 33. Turning the knob 59 in the opposite direction pushes the wedge 37 to the right and swings the left-hand end of the corner of the hardened block 11 away from the knife.

The support 27 by which the table 9 is carried in the manner described above is itself mounted for bodily vertical adjustment and for angular adjustment about a horizontal axis, the mounting of the support upon the frame of the machine being similar to the mounting of the table 9 on the support. To this end four bosses, two of which are shown in Fig. 3, have flat alined vertical faces against which flat faces on the vertical portion of the support 27 rest. Referring more particularly to Figs. 3 and 4, the downwardly extending vertical portion of the support 27 has formed on that side of it which faces the frame of the machine an undercut guideway 127 in which the opposite edges of a block 61 are slidably received. This block 61 and the support are held stationary, except when the support 27 is being adjusted, by a screw 63 the flat head of which is received in a recess in the frame 65 of the machine and is fastened to the frame by a small screw 67. The stem of the screw 63 passes through a bore in the block 61 and has threaded on its end a nut 69 through which passes a small bar 71 by which the nut may be turned. When the nut is tight the support 27 is held rigid with the block, and both parts are held stationary. When the nut is loose the support may slide on the block, and the table and block may swing in unison about the horizontal axis of the screw 63. The support is urged downward at all times by two compression springs 73, 75, one end of each spring being located in a socket in the block 61 and the other end of each spring resting upon a cross bar 77 fastened by cap screws 79 to the bottom of the support 27. This tendency of the springs to move the support down is resisted by two cams in the form of wedges 81, 83 which engage with their lower inclined faces stops in the form of horizontally extending rolls 85, 87 carried by the frame, the upper flat alined faces of the wedges being in sliding contact with a flat face formed on the support. The wedge 81 is fastened by a pin 89 to a rod 91 which passes through the wedges, said rod having on its right-hand end a right-hand thread and on its left-hand end a left-hand thread. A coiled compression spring 93, which bears with its right-hand end against a part of 95

the support 27 and with its left-hand end against the bottom of a socket in the wedge 81, urges the wedge and the rod at all times to move to the left, the location of the wedge and the rod at any time depending upon the position of a knob 95 which is threaded on the right-hand end of the rod and abuts a boss on the support 27. A second coiled compression spring 97, which bears with its right-hand end against the wedge 81 and with its left-hand end against the bottom of a socket in the wedge 83, urges the wedge 83 at all times to move along the rod to the left (Fig. 4) as far as is permitted by a second knob 99 which is threaded on the left-hand end of the rod, the thread on this end of the rod being a left-hand thread. When the nut 69 is loose, the support 27 may be adjusted bodily up and down as well as angularly in a vertical path about the horizontal axis of the screw 63. To adjust the support 27 bodily up, the knob 95 is turned right hand on the right-hand thread of the rod 91, as indicated by the arrow. This lifts the support bodily against the force of the springs 73, 75. Turning the knob 95 in the opposite direction permits the springs 25 to lower the support. To swing the support about the axis of the horizontal screw 63, the left-hand knob 99 is turned to cause the wedge 83 to move along the rod 91. Turning the knob 99 left hand on the left-hand thread, as indicated by the arrow, moves the wedge 83 to the right and raises the left-hand side of the support 27. Turning the knob 99 in the opposite direction permits the spring 73 to lower the left-hand side of the support 27. Thus by turning the four knobs 55, 59 (Fig. 5) and 95, 99, the forward operative edge of the table 9 (Fig. 3), which is constituted by the left-end upper edge or corner of the hardened block 11, may be brought into exact parallel relation with the axis of the roll 17 and 40 may be raised and lowered.

It is desirable (Fig. 3) that the operative edge or corner of the hardened block 11 be exactly below and in line with the axis of the rubber roll 17, and that the edge of the knife 13 be parallel to the operative edge of the block and spaced from it horizontally a distance of the order of from .005 to .006 of an inch. The mechanism for adjusting the table 9 has been described. The knife 13 (Fig. 5) is clamped to a part of the frame of the machine which has an inclined flat supporting face, said knife being held in adjusted position by cap screws 101 which pass through slots 103 in the knife and are threaded into the frame. The knife may be adjusted along its support by means of two adjusting screws 105 which are threaded into the frame and have heads which engage the back of the knife. When it is desired to adjust the knife, the cap screws 101 are loosened and one or both of the adjusting screws 60 105 are turned, depending upon whether it is desired to adjust the knife angularly or bodily. In order to facilitate the accurate adjustment of the hardened block 11 and the knife 13 into positions in which the operative corner of the block 65 is below and parallel to the axis of the rubber roll and the edge of the knife is parallel to said corner and properly spaced horizontally from it, a gaging mechanism is provided which indicates by means of pointers and scales when this desired 70 position of parts has been attained.

The gaging mechanism (Figs. 5, 6) comprises a pointer-and-scale mechanism for each end of the hardened block 11 and a pointer-and-scale mechanism for each end of the knife 13, there being thus four such mechanisms. Referring to Fig.

5, the two pointer-and-scale mechanisms for the knife are indicated as a whole respectively at A and B; and the two pointer-and-scale mechanisms for the hardened block 11 are indicated as a whole respectively at C and D. Two of the 5 pointer-and-scale mechanisms, A and D, one for the knife and one for the hardened block, are mounted in a bracket 107 having a horizontally extending base which is fastened by screws 109 and a dowel pin 111 upon the top of one of the 10 stationary bearings 113 (Fig. 4) through which is vertically slidable one of the rods, later to be described, which support the rubber feed roll 17, the base of the bracket 107 having a hole somewhat larger than the diameter of the slide rod. 15 The other two pointer-and-scale mechanisms are similarly mounted in a similar bracket 115 (Fig. 5) at the other side of the machine. Since the two pointer-and-scale mechanisms A and D are substantially the same respectively as the two 20 pointer-and-scale mechanisms B and C, only the mechanisms A and D will be described in detail.

Referring more particularly to Fig. 6, the bracket 107, the pointer-and-scale mechanism indicated at D and the pointer-and-scale mech- 25

anism indicated at A are shown. The bracket 107 has a horizontal base, as has been described, through which the fastening screws 109 pass. Extending up from this base are two thin walls with a narrow space between them to accommo- 30

date the pointers. The inner wall 117 is compa- 35

ratively low. The outer wall 119 is consider- 40

ably higher and is forked to provide two upwardly extending arms, on the tops of which are marked scales, the scale 123 (Fig. 5) being for 45

one end of the knife and the scale 121 for one 50

end of the hardened block. Referring again to 55

Fig. 6 the pointer-and-scale mechanism D for one end of the hardened block will be described. The pointer is formed by an outward bend at the 60

upper end of a vertical lever 125 which is pivoted at its lower end about a small pivot 129 carried by the upright walls 117, 119 of the bracket 65

107. At its lower end the pointer lever 125 has 70

two horizontal extensions one to the right and 75

the hardened block are also set so that when the two pointers point to a selected numeral (the numeral 5 as illustrated) the forward edge of the hardened block is not only parallel to but is also directly below the axis of the feed roll.

After the hardened block 11 has been properly located by turning the knobs 55, 59 and observing the two scales 121, 142, the knife is adjusted toward or from the block as well as angularly, if necessary, by turning the adjusting screws 105 together or separately to bring the edge of the knife into parallel relation with the forward edge of the corner of the hardened block and to locate the edge of the knife at the proper distance lengthwise of the machine from said corner of the block. To facilitate such adjustment of the knife the two pointer-and-scale mechanisms A and B are provided; and since, as has been stated, these mechanisms are substantially alike, only the mechanism A will be described in detail. Referring again to Fig. 6, the pointer for the scale 123 is formed by the upper bent end of a pointer lever 143 pivoted at its lower end about a small pivot 145 carried by the two upright walls 117, 119 of the bracket 107. At the lower end of the pointer lever are two oppositely extending extensions one on each side of the pivot 145. To the end of the right-hand extension is fastened the lower end of a tension spring 147 the upper end of which is fastened to a pin 149 driven into the wall 119, said spring tending at all times to swing the pointer lever 143 counterclockwise as far as a set screw 151 will permit. This set screw is threaded through the split left-hand extension at the lower end of the pointer lever 143 and is held in adjusted position by a pinch screw 153. The set screw 151 abuts against one end of a bell-crank lever 155 which swings about a pivot 157 carried by the upright walls 117, 119 and carries at its upper end a pin 159 the end of which is half-round to form a flat face against which one end (the right-hand end as viewed in Fig. 6) of the edge of the knife abuts. To provide space for this pin and a corresponding one on the opposite side of the machine, as well as to provide space when the hardened block 11 has been turned over to render another corner of it operative, the hardened block is cut away at its opposite ends, as shown best in Figs. 4 and 5. The pointer-and-scale mechanism B at the other end of the knife is substantially the same as the pointer-and-scale mechanism A. Consequently when the knife is adjusted bodily forward or back, the pointers move equally along their respective scales 123, 124; but when the knife is adjusted angularly only one pointer moves. The two pointer and scale mechanisms are so set by means of the set screws, one of which is shown at 151 in Fig. 6, that when the pointers both point to the same numeral on both scales the knife is parallel to the operative corner of the hardened block 11 and is spaced from said corner, lengthwise of the machine, a distance which is indicated in thousandths of an inch by the numerals on the scales. As illustrated in Fig. 5, this distance is .005 of an inch. It will be noted (Fig. 6) that the rolls 141, 159 extend out toward the observer and that holes are provided in the plate 117 to permit movement of these rolls.

The hardened block 11 (Fig. 5) is fastened in a recess in the forward end of the table 9 by screws 161 which pass through slots in the block and are threaded into the table. The block may therefore be adjusted and may be turned over

widthwise or lengthwise to expose a fresh sharp corner to the knife when desired.

The rubber covered feed and presser roll 17 is capable of being adjusted vertically as well as angularly and is mounted for yielding movement. To this end (Fig. 4) it is carried by yokes 163, 165 which are fastened respectively by taper pins 167, 169 to the upper ends of vertical slide rods 171, 173. The slide rod 171 is slidable in bearings 113 and 174, and the arms of the yoke 163 carry aligned pins 175 (Fig. 6) which extend through the arms of the yoke from the outside and into sockets in a bearing member 177. The other yoke 165 (Fig. 4) has pins, one of which is indicated at 179, which extend into a bearing 181. The feed roll shaft 182 extends through and is supported by the bearing members 177, 181 and carries the feed roll which consists of a thick rubber cover vulcanized to a metal hub 183, said hub being fastened to the shaft 182 by a taper pin 185. The slide rod 171 rests with its lower end upon the inclined face of a cam in the form of a wedge block 187, and the slide rod 173 rests similarly upon the inclined face of a second wedge block 189, the slide rods being urged downwardly at all times respectively by coiled compression springs 191, 193. The spring 191 engages with its upper end the under side of the bearing 113 and rests with its lower end upon a nut 195 which may be turned to vary the tension of the spring, the nut being threaded upon a sleeve 197 the hub of which is fastened to the slide rod by a taper pin 199. A check nut 201 is provided for locking the nut 195 in adjusted position. The spring 193 on the slide rod 173 is mounted in the same manner as is the spring 191 on the slide rod 171, there being an adjusting nut 203 to adjust the tension of the spring 193. The two slide rods are thus urged downward at all times by springs the tension of which may be varied. The wedge block 187, which like the other wedge block 189 is slidable in a bore in the frame of the machine, is pinned at 207 to a rod 209 which has a right-hand thread at its right-hand end and a left-hand thread at its left-hand end. The wedge block 189 is slidable on the rod, being urged continually to the left by a coiled compression spring 210 the right-hand end of which engages a collar 211 fastened to the rod, the position of the block on the rod being determined by a knob 213 which is threaded on the left-hand end of the rod and engages the left-hand end of the wedge block. On the right-hand end of the rod is threaded a second knob 215 which is held from longitudinal movement by a thin plate 217 fastened to the frame of the machine and extending into a transverse groove in the knob. Turning the knob 215 right hand on its right-hand thread, as indicated in Fig. 4, pulls both wedge blocks 187, 189 to the right and raises the feed roll bodily. Turning the knob 215 in the opposite direction permits the springs 191, 193 to lower the feed roll bodily. Turning the knob 213 left hand on its left-hand thread, as indicated in Fig. 4, pushes the wedge block 189 to the right and raises the left-hand end of the feed roll. Turning the knob 213 in the opposite direction permits the spring 210 to move the wedge block 189 to the left whereupon the spring 193 lowers the left-hand end of the feed roll.

Referring to Figs. 1, 2 and 3 the insoles are fed one by one over the table 9 to the knife and the combined feed and presser roll, as has been explained above. The stack of insoles 100 rests upon the upper run of a belt 219, being held in 75

stacked formation by side walls 221, 223 and a front wall 225 of a magazine, of which the upper run of the belt forms the bottom. The side wall 223 is carried at the inner ends of horizontal rods 227 slideable in bores in bosses formed on the supporting casting 45 and held in adjusted positions by set screws 229; and the other side wall 221 is similarly carried by slide rods 231 adjustably held by set screws 233. The front wall 225 is vertically adjustable so as to permit only one insole at a time to be fed from the bottom of the stack by the belt. Integral with the front wall, one at one end of the wall and one at the other, are two bosses 235, said bosses having vertical bores to receive respectively vertical rods 237, carried by the casting 45, on which the bosses are vertically slideable. Compression springs 238 urge the bosses upward at all times, and nuts 239 threaded on the upper ends of the rods provide means for adjusting the front wall 225 up and down. The feeding belt 219 passes around two rolls 241, 243 the bearings of which are slidably mounted in the casting 45, adjusting screws 245 being provided for adjusting the bearings of the two rolls to maintain a proper tension on the belt. The middle of the upper run of the belt is supported by an idle roll 247 to prevent sagging of the upper run due to the weight of the stack of insoles.

The insoles, after the grain has been removed from them, pass over a plate 249 and are stacked in a receptacle. Both the plate 249 and the receptacle are supported on two horizontal rods 251, 253 which are carried by the frame of the machine. The plate 249 (Fig. 2) has a boss at one end provided with a bore through which the rod 251 passes, the boss being provided with a set screw 255. Near the middle of the other end of the plate 249 is an extension which rests upon the rod 253. The plate may thus be adjusted along the rods and held in adjusted position. The receptacle is supported on a base in the form of an inclined plate 257 (Figs. 2, 3) rigidly fastened by screws 259 to the lower substantially horizontal portion of a generally right-angled casting 261, the upper end of the vertical arm of which has a boss provided with a bore to receive the rod 253. The boss on the casting 261 has an enlarged right-hand end (Fig. 2) which is fastened by screw bolts 263 to a cross-bar 265 which has bores in its opposite ends to receive respectively the rods 253, 251 and is bent downward so as to extend beneath the plate 249 at a distance therefrom. The casting 261, which supports the receptacle in which the insoles are stacked, may thus be slid along the rods 251, 253 and will remain in any position into which it is moved. Adjustably fastened to the base plate 257 by screws 267 are two angle irons 269, the screws passing through slots in the horizontal arms of these angle irons and being threaded into the base; and to the upright arms of these angle irons is fastened a guide-plate 271 which serves to guide the insoles into the receptacle. The receptacle itself comprises a side wall 273, an end wall 275 and a bottom 277 which are integral with one another. The receptacle is normally upright as shown in position to receive insoles, but it may be swung down about the axis of a small rod 279 to facilitate removal of a stack of insoles which have been operated upon. This rod passes loosely through bores in two blocks 281, which are in turn fastened to the wall 273 of the receptacle, and through bores in two other blocks 283 which are adjustably fastened to the base 257 by screws 285, said screws

passing through slots in portions of these blocks, and being threaded into the base. The rod 279 is held in place by cotter pins, one of which is shown at 286 in Fig. 1. It is thus possible to adjust the receptacle crosswise of the base 257 and to swing it down about the axis of the rod 279 so as to facilitate the grasping of a stack of finished insoles and the removing of the stack from the receptacle.

The machine is driven from a motor 287 (Fig. 10) by means of a belt 289 which passes around a pulley on the motor shaft and around a pulley 291 on a countershaft. A second belt 293 runs around a pulley 295 on the countershaft and around a pulley 297 on the feed roll shaft 182; and a third belt 299, which is crossed, runs around a pulley 301 also on the feed roll shaft and around a pulley 303 fast to a shaft 305 which carries the roll 241, the direction of travel of these belts being indicated by the arrows in Fig. 1.

In the operation of the machine the insoles or other pieces of work are fed one by one from the bottom of the stack in the magazine, pass over the table or work support 9 to the rubber roll 25 and the knife, and thence over the plate 249 into stacked relation in the receptacle.

It should be noted (Fig. 3) that the feeding belt 219 is substantially as wide as the knife, that both these members are wider than the insoles which are being operated upon, and that the side walls 221, 223 are both adjustable across the belt 219. With this construction it is possible to adjust the two walls 221, 223 in the same direction across the belt and thus to direct the insoles to a selected locality on the cutting edge of the knife. Thus, if a locality on the edge of the knife becomes dull from continued use or becomes nicked, the insoles may be fed to another locality.

Although the invention has been set forth as embodied in an illustrated machine, it should be understood that the invention is not limited in the scope of its application to the particular machine which has been shown and described.

Having thus described the invention, what I claim as new and desire to secure by Letters Patent of the United States is:

1. A machine of the class described having, in combination, a knife, a work-supporting member having an unyielding gaging edge the position of which with respect to the edge of the knife determines the thickness of the skiving which will be removed, an internally yieldable presser between which and the knife and gaging edge the work is fed, and means whereby the member having the gaging edge may be adjusted bodily in a path which is parallel to its work-supporting surface and angularly about an axis which is perpendicular to said surface.

2. A machine of the class described having, in combination, a knife, a work-supporting member having an unyielding gaging edge the position of which with respect to the edge of the knife determines the thickness of the skiving which will be removed, an internally yieldable presser between which and the knife and gaging edge the work is fed, and means whereby the member having the gaging edge may be adjusted bodily in a path which is perpendicular to its work-supporting surface and angularly about an axis which is parallel to said surface.

3. A machine of the class described having, in combination, a knife, a table, a presser roll between which and the table the work is fed to

the knife, and a support for the table with respect to which the table is bodily and angularly adjustable.

4. A machine of the class described having, in combination, a knife, a table, a presser roll between which and the table the work is fed to the knife, and a support for the table with respect to which the table is bodily and angularly adjustable, said support being mounted on the frame of the machine and being bodily and angularly adjustable with respect to said frame.

5. A machine of the class described having, in combination, a knife, a substantially horizontal table, and a presser roll between which and the table the work is fed to the knife, said table being adjustable bodily in both horizontal and vertical paths as well as angularly about vertical and horizontal axes.

6. A machine of the class described having, in combination, a knife, a substantially horizontal table, a presser roll between which and the table the work is fed to the knife, said table being adjustable bodily in both horizontal and vertical paths as well as angularly about vertical and horizontal axes, and four operator-controlled members manipulation of which separately effects one of the four adjustments while maintaining the other three unchanged.

7. A machine of the class described having, in combination, a knife, a table, a presser roll between which and the table the work is fed to the knife, and means whereby the table may be adjusted bodily in a path which is parallel to its work-supporting surface and angularly about an axis which is substantially perpendicular to said surface.

8. A machine of the class described having, in combination, a knife, a table the forward edge of which serves as a gage to determine the thickness of the skiving removed by the knife, a presser roll of yieldable construction between which and the table the work is fed to the knife, and means whereby the table may be adjusted bodily in a path which is parallel to its work-supporting surface and angularly about an axis which is substantially perpendicular to said surface.

9. A machine of the class described having, in combination, a knife, a table, a presser roll between which and the table the work is fed to the knife, said table being mounted for adjustment bodily forward and back toward and from the knife and for angular adjustment about an axis substantially perpendicular to the surface of said table, a member manipulation of which effects the bodily adjustment, and a second member manipulation of which effects the angular adjustment.

10. A machine of the class described having, in combination, a knife, a table the forward edge of which serves as a gage to determine the thickness of the skiving removed by the knife, a yieldable presser roll between which and the table the work is fed to the knife, said table being mounted for adjustment bodily forward and back toward and from the knife and for angular adjustment about an axis substantially perpendicular to the surface of said table, a member manipulation of which effects the bodily adjustment, and a second member manipulation of which effects the angular adjustment.

11. A machine of the class described having, in combination, a knife, a table, a presser roll between which and the table the work is fed to the knife, a support for the table with respect to which the table is bodily and angularly adjust-

able, a pair of cams carried by the table and adjustable at will either in unison or with respect to each other, and connections between the cams and the support such that adjusting the cams in unison adjusts the table bodily and adjusting them with respect to each other adjusts the table angularly.

12. A machine of the class described having, in combination, a knife, a table, a presser roll between which and the table the work is fed to the knife, a support for the table, a block having a sliding connection with the table, a pivot connecting the block and the support whereby the table may slide bodily with respect to the block and the block and table may swing angularly about the axis of the pivot, and a manually operable member which acts through the pivot to lock the block and the table rigidly to the support.

13. A machine of the class described having, in combination, a knife, a table, a presser roll between which and the table the work is fed to the knife, a support for the table, a block having a sliding connection with the table, a pivot connecting the block and the support whereby the table may slide bodily with respect to the block and the block and table may swing angularly about the axis of the pivot, stops carried by the support, cams carried by the table, springs between the block and the table tending at all times to hold the cams in contact with the stops, means for moving the cams in unison to cause bodily sliding movement of the table on the block, and means for moving one cam with respect to another to cause angular adjustment of the block and table.

14. A machine of the class described having, in combination, a knife, a table, and a presser roll between which and the table the work is fed to the knife, said table being mounted for bodily adjustment in a path which is perpendicular to the work-supporting surface of the table and for angular adjustment about an axis which is perpendicular to said path.

15. A machine of the class described having, in combination, a knife, a table, a presser roll between which and the table the work is fed to the knife, said table being mounted for bodily adjustment in a path which is perpendicular to the work-supporting surface of the table and for angular adjustment about an axis which is perpendicular to said path, a member manipulation of which effects the bodily adjustment, and a second member manipulation of which effects the angular adjustment.

16. A machine of the class described having, in combination, a knife, a table, a presser roll between which and the table the work is fed to the knife, a support for the table, said support being bodily and angularly adjustable with respect to the frame of the machine, a pair of cams carried by the support and adjustable at will either in unison or with respect to each other, and connections between the cams and the frame such that adjusting the cams in unison adjusts the support bodily and adjusting them with respect to each other adjusts the support angularly.

17. A machine of the class described having, in combination, a knife, a table having a gaging edge, a presser roll between which and the table the work is fed to the knife, means whereby the table may be adjusted bodily in a path parallel to its work-engaging surface and angularly about an axis perpendicular to said surface, and indicating mechanism operated by movement of the

table to indicate when the gaging edge of the table is properly located with respect to the axis of the roll.

18. A machine of the class described having, in combination, a knife, a table having a gaging edge, a presser roll between which and the table the work is fed to the knife, means whereby the table may be adjusted bodily in a path parallel to its work-engaging surface and angularly about an axis perpendicular to said surface, and indicating mechanism operated by movement of the table to indicate when the gaging edge of the table is properly located with respect to the axis of the roll, said indicating mechanism including two scales one at each end of said gaging edge, a pointer for each scale, and two members held in engagement with the table and connected respectively each with one of the pointers.

19. A machine of the class described having, in combination, a knife, a table having a gaging edge, a presser roll between which and the table the work is fed to the knife, means whereby the knife may be adjusted bodily and angularly, and indicating mechanism operated by movement of the knife to indicate when the edge of the knife is properly located with respect to the gaging edge of the table.

20. A machine of the class described having, in combination, a knife, a table having a gaging edge, a presser roll between which and the table the work is fed to the knife, means whereby the knife may be adjusted bodily and angularly, indicating mechanism operated by movement of the knife to indicate when the edge of the knife is properly located with respect to the gaging edge of the table, said indicating mechanism including two scales one at each end of the edge of the knife, a pointer for each scale, and two members held in engagement with the knife and connected respectively to the pointers.

21. A machine of the class described having, in combination, a roll and a knife between which the work is fed, and mechanism for adjusting the roll bodily toward and from the edge of the knife and angularly, said mechanism comprising two manually operable members, manipulation of one of which effects the bodily adjustment and manipulation of the other of which effects the angular adjustment.

22. A machine of the class described having, in combination, a roll and a knife between which the work is fed, and mechanism for adjusting the roll bodily toward and from the edge of the knife and angularly, said mechanism comprising rods by which the opposite ends of the roll are supported, cams engaging said rods, and means for adjusting the cams in unison and with respect to each other.

23. A machine of the class described having, in combination, a roll and a knife between which the work is fed, and mechanism for adjusting the roll bodily toward and from the edge of the knife and angularly, said mechanism comprising rods by which the opposite ends of the roll are supported, cams engaging said rod, a threaded rod upon which the cams are mounted, and hand-holds threaded on the rod.

24. A machine of the class described having, in combination, a knife, a member having an unyielding gaging edge the position of which with respect to the edge of the knife determines the thickness of the skiving which will be removed from a piece of work, a magazine comprising a belt upon which a stack of pieces of work rest and two side walls, and means for operating the belt to feed the pieces of work one by one from the bottom of the stack over the gaging edge to the knife and roll, the belt and the knife being wider than the pieces to be operated upon, and the side walls being adjustable transversely of the belt to permit the pieces of work to be directed to different localities on the edge of the knife.

25. A machine of the class described having, in combination, a knife, a member having an unyielding gaging edge the position of which with respect to the edge of the knife determines the thickness of the skiving which will be removed from the work, a driven roll, a belt one run of which supports a stack of pieces of work, means for operating the belt to feed the pieces of work one by one from the bottom of the stack over the gaging edge to the knife and roll, and a receptacle in which the finished pieces of work are received, said receptacle being mounted for adjustment toward and from the knife and roll.

CHARLES E. HOOD.
